UNITED STATES PATENT OFFICE.

MYRICK R. ALLEN, OF LEWISBURG, TENNESSEE.

CAR-COUPING.

SPECIFICATION forming part of Letters Patent No. 288,754, dated November 20, 1883.

Application filed October 13, 1883. (No model.)

To all whom it may concern.

Be it known that I, MYRICK R. ALLEN, a citizen of the United States, residing at Lewisburg, in the county of Marshall and State of Tennessee, have invented new and useful Improvements in Car-Couplings, of which the following is a specification.

This invention relates to that class of car-couplings in which a pivoted tumbler located within the draw-head is adapted to support the coupling-pin preparatory to coupling, and to release and allow the tumbler to drop when the tumbler is pushed back by the link entering the draw-head.

15 The object of my invention is to improve the construction of the draw-head and tumbler, whereby certainty of action is at all times insured, and also to provide simple and efficient means for uncoupling from either the top or side of a car without going between two adjacent cars. These objects I attain by the means illustrated in the accompanying drawings, and hereinafter particularly described.

Figure 1 of the drawings is a front elevation 25 of the coupling devices. Fig. 2 is a side elevation with the draw-head in section. Fig. 3 is a front elevation of a modification of the draw-head and tumbler with the other devices connected therewith. Fig. 4 is a side elevation thereof with the draw-head in section.

In the drawings, the letter A indicates the draw-head, which is formed with the usual bell-mouth, and has formed in its bottom a longitudinal channel or recess, F, to receive 35 the lower end of the tumbler D, so that the said lower end will be below the bottom side of the space within the draw-head, and hence the link in being pushed back cannot slip under and back of the tumbler, and the tumbler 40 cannot be drawn out of the head.

The link B (shown in dotted lines) and the coupling-pin C are both of ordinary construction, the latter being arranged to work within a hole, e, formed vertically through the draw-head. Preparatory to coupling, the pin is supported in the elevated position shown, by means of a pivoted tumbler, D, that is arranged within the draw-head and hinged at its two upper corners, d, upon a horizontal cross-rod or pivot, E, which is secured at its ends in the sides of the draw-head.

The tumbler is preferably of the form shown in Figs. 1 and 2, with a curved front face, and is formed near its upper end with a seat, d³, which preferably is of a concave form, so as 55 to receive the end of the coupling-pin and prevent it from slipping sidewise, and which it supports in a vertical position when the link is out of the draw-head. When the tumbler is of the form shown in Figs. 1 and 2, it will 60 hang vertically when the link is out of the head, and its weight will counterbalance that of the coupling-pin, so that it will not be pushed back by it. When the link is pushed against the front face of the tumbler, the latter is 65 pressed backward and upward into the space within the draw-head, when the coupling-pin is free to fall and enter the link to hold it in place. When the tumbler is so pressed back, it will rest upon the top of the rear part of 70 the link and hold it in a horizontal position, so as to readily enter the draw-head of the car to be coupled thereby. As soon as the pin is withdrawn from the link the tumbler will press the same outward and assume its 75 vertical position. The curved front face of the tumbler permits it to be more easily pushed back to effect the coupling.

The device for raising the pin in uncoupling from either the top or side of the car is 80 constructed and arranged as follows: A bar, G, secured to the end of the car, is formed or provided with a pair of parallel horizontal arms, g', that extend out at right angles to the end of the car, and a vertical lifting-rod, H, 85 is arranged to slide through perforations in the ends of said arms. The coupling-pin is connected by a chain with the lower end of the vertical lifting bar, and the latter is formed with suitable stops, which arrest its downward 90 movement through the horizontal arms after the coupling-pin has entered the draw-head and engaged the link. This vertical lifting-rod can be operated in two ways, one being by depressing a foot-lever, I, located on top 95 of the car, and the other being by depressing a hand-lever, K, that is pivoted to the end of the car and extended out from the side of the same.

The foot-lever I is pivoted in a standard, i, 100 upon the top of the car, and connected at one end with the lifting-rod. By this means a

brakeman on top of the car can depress the lever with his foot, and thereby raise the lifting-rod and pin, and at the same time manipulate the brake-wheel with his hands. The 5 hand-lever K, that is pivoted to the end of the car, connects at its inner end by a link, L, with a horizontal arm, M, secured to the lifting-rod. This hand-lever K works between the end of the car and the guide-plate l, and is 10 pivoted at its inner end to the said link. The horizontal arm M extends from a collar, m, fixed upon the lifting-rod, and at its opposite end said arm is provided with fixed washers or collars m', between which the link is manipulated. It will be observed that the collar m upon the lifting-rod constitutes one of the 15 stops for limiting its disk, the maining stop being located at the top end of said rod. To lock the lifting-rod and coupling-pin in an elevated position a pin, N, is connected with the 20 end of the car by a chain and staple in such position that after depressing the outer end of the hand-lever, and thereby elevating the lifting-rod, the pin N can be inserted above the 25 lever in a socket formed in the car, and thus lock the said lever end down.

In Figs. 3 and 4, I show a modification of the tumbler and the draw-head; but the operation in all essentials is the same as that of the preferred form shown in Figs. 1 and 2. The devices for raising the pin are the same. In the modification the draw-head has formed in its rear head a recess, a, for receiving one 30 end of the coupling-link when the latter is passed into the draw-head, so as to support the link in a horizontal position, ready for coupling with the coupling devices of the next car. In the modification the channel F continues back to the rear wall in the draw-head, and 35 then runs up vertically in said wall, so that after the link has been pushed back and received into the transverse recess a the tumbler will be swung back and up into the vertical continuation F' of the channel F, and being 40 behind the link will rest upon the end of the same and assist in holding it in a horizontal position, and be in readiness to swing down to a vertical position as soon as the link is withdrawn. The lower portion of the tumbler 45 is enlarged or weighted, as indicated at d', so as to insure its assuming a vertical position after the link has been removed from the draw-head, and also to cause it to counterbalance the weight of the coupling-pin, which, as already 50 stated, preparatory to coupling, rests upon a seat, d'', in this instance formed by a flange projecting forward from the upper end of the tumbler. The flange projects at right angles to the front face of the tumbler, and is 55 formed with a flange, d'', at its sides, so as to prevent the pin from slipping off sidewise. Under my construction, when the link is inserted in the draw-head and the pin is down, the tumbler rests on the link behind the pin 60 and holds it to its adjustment, and when the link is out of the draw-head the tumbler hangs 65

forward and holds up the pin until the link in the approaching car enters the draw-head.

It will thus be seen that a very perfect coupling is effected in a very simple manner, with 70 certainty, and without endangering the lives of brakemen by passing between the cars to effect the coupling and uncoupling thereof.

Having thus described my invention, what I claim is—

1. In a car-coupler, the combination of a draw-head formed with a channel or recess in its bottom, and a tumbler pivoted therein, the said tumbler being formed forward of and below its pivotal point with a concave seat for 80 the coupling, and adapted to fit within said recess when the link is not within the head, and to rest on the link when it is therein, and hold the same in position for coupling with the other coupler, substantially as described. 85

2. In a car-coupler, the combination, with a draw-head, of the tumbler pivoted therein, and formed with a curved face receding, as shown, and forward of its pivotal point, with 90 a concave seat for the coupling-pin, substantially as described.

3. The combination, in a car-coupling, of the coupling-pin and the pivoted tumbler D, with the draw-head formed with the longitudinal and vertical channels F F', for the lower end of the tumbler to swing in, and with the recess g, for receiving an end of the link after the tumbler has been swung to the rear of said recess, substantially as described. 95

4. The combination, in a car-coupling, of the draw-head and its pivoted tumbler with the coupling-pin C, the vertical lifting-rod H, connected with the coupling-pin, a foot-lever connected with said lifting-lever, and located upon the top of the car, and a hand-lever, K, 100 pivoted to the end of the car, and connected by a link with said lifting-rod, whereby the car can be uncoupled from either the top or side, substantially as described. 105

5. The combination, with the draw-head and its pivoted tumbler, of the coupling-pin C, the vertical lifting-rod H, passing through horizontal arms g, and flexibly connected with the coupling-pin, the foot-lever I, pivoted to a standard on top of the car and connected with 110 the upper end of the lifting-rod, and the hand-lever K, pivoted to the end of the car and connected by a link with an arm, M, extending horizontally from the lifting-rod, said members being constructed and organized substantially as described. 115

6. In a car-coupler, the combination of the coupling-pin, the vertical lifting-rod connected with the coupling-pin, and provided with stops for limiting its downward movement, the foot-lever pivoted at the top of the car and connected with the upper end of the lifting-rod, and the hand-lever pivoted to the end of the car and connected by a link with the arm extending horizontally from the lifting-rod, substantially as described. 125

7. The combination of the coupling-pin, the

arms extending horizontally from the car, the lifting-lever provided with stops, and passing through said arms and connecting with the pin, the hand-lever pivoted to the car, the 5 arm rigidly connected at one end to the lifting-lever, and provided with the collars at the opposite end, and the link connecting the said arm and the hand-lever, substantially as described.

In testimony whereof I have hereunto set to my hand in the presence of two subscribing witnesses.
